(57) **CLAIM**

The ornamental design for a container cap for package, as shown and described.

DESCRIPTION

FIG. 1 is a top side perspective view of a container cap for package in accordance with our new design;

FIG. 2 is a bottom side perspective view of the container cap for package in accordance with our new design of FIG. 1; FIG. 3 is a front elevational view of the container cap for package in accordance with our new design of FIGS. 1 and 2;

FIG. 4 is a left side elevational view of the container cap for package in accordance with our new design of FIGS. 1 to 3; FIG. 5 is a top plan view of the container cap for package in accordance with our new design of FIGS. 1 to 4; FIG. 6 is a bottom plan view of the container cap for package in accordance with our new design of FIGS. 1 to 5; FIG. 7 is an end view of the container cap for package in accordance with our new design of FIGS. 1 to 6 as taken along a section line 7-7 in FIG. 3;

FIG. 8 is a cross-sectional view of the container cap for package in accordance with our new design of FIGS. 1 to 7 as taken in the direction of line 8-8 in FIG. 3;

FIG. 9 is an end view of the container cap for package in accordance with our new design of FIGS. 1 to 8 as taken along a section line 9-9 in FIG. 3;

FIG. 10 is an end view of the container cap for package in accordance with our new design of FIGS. 1 to 9 as taken along a section line 10-10 in FIG. 3;

FIG. 11 is an end view of the container cap for package in accordance with our new design of FIGS. 1 to 10 as taken along a section line 11-11 in FIG. 3;

FIG. 12 is a cross-sectional view of the container cap for package in accordance with our new design of FIGS. 1 to 11 as taken in the direction of line 12-12 in FIG. 5; and,

FIG. 13 is an end view of the container cap for package in accordance with our new design of FIGS. 1 to 12 as taken along a section line 13-13 in FIG. 6.

(Continued)

The rear elevational view is omitted because it is identical to the front elevational view. The right side elevational view is omitted because it is identical to the left side elevational view.

The cross-sectional views of FIGS. 8 and 12 are provided to clarify the exact contour or configuration of the exterior of the container cap for package, and no attempt is made to illustrate features of internal construction.

The container cap for package in accordance with our new design is assumed to be screwed on a mouth portion of a packaging container body.
